DISCHARGE DEVICE

Otis W. Pike, Schenectady, N. Y., assignor to
General Electric Company, a corporation of
New York

Application September 30, 1938, Serial No. 232,590

4 Claims. (Cl. 250—27.5)

The present invention relates to discharge devices and more particularly to improvements in envelope structures for such devices.

It has proven convenient in the fabrication of 5 discharge devices to utilize envelope structures comprising an elongated glass or metal cylinder forming the main body of the envelope and transverse headers closing the ends of the envelope. To facilitate joining these parts and for certain 10 other reasons, it is desirable to form the headers of relatively thin metal having a thickness, say, on the order of 100 mils or less. This occasions no difficulty in connection with small tubes, but in large devices such as mercury pool tubes or 15 the like, the presence of a relatively large area of thin metal raises the danger of buckling due to pressure differences existing between the exterior and the interior of the envelope.

It is an object of my present invention to 20 provide means for effectively overcoming this danger without, at the same time, losing the advantages associated with a thin header construction. This is accomplished by applying to a selected portion of the header a reinforcing 25 plate which is integrally joined to the header by means hereinafter to be described.

The features which I desire to protect herein are pointed out in the appended claims. The invention itself together with further objects and 30 advantages thereof may best be understood by reference to the following description taken in connection with the drawing in which Fig. 1 shows in longitudinal section a discharge device suitably embodying the invention; Fig. 2 is 35 an enlarged view showing a detail of the structure of Fig. 1; Fig. 3 comprises an alternative embodiment of the invention; and Fig. 4 is an enlarged detail of the fragmentary portion of Fig. 3.

Referring particularly to Fig. 1, there is shown 40 a pool-type discharge device adapted for relatively high power use. This comprises an elongated metal envelope comprising an outer cylinder 10 and an inner cylinder 11 which is spaced from the outer cylinder so as to provide a water jacket. The outer cylinder 10 may comprise a 45 straight tubular section of sheet steel having a thickness, say, of 100 mils. The inner cylinder 11 is preferably constituted of a chromium steel such as, for example, that sold as "stainless steel". The function of the chromium content is to prevent 50 the infiltration of hydrogen from the water bath to the interior of the envelope.

Since stainless steel is a relatively expensive 55 commodity, it is desired to use no more than is absolutely necessary. To this end the cylinder 11 is made of relatively thin material, say on the order of 100 mils or less. Its ends are provided with spun-out enlargements 14, 15 which are adapted to interfit with the cylinder 10. Line-welded joints are provided between the two cyl-

inders so as to render the space between them water-tight. The ends of the envelope are respectively closed by dished metal members which comprise transverse header portions 17, 18 having peripheral flanges numbered 19 and 20. 5

Within the envelope there is provided appropriate electrode structure including an anode 21, a mercury pool cathode 22 and a make-alive electrode 23, constituted of a semi-conductive material. The anode 21 and the electrode 23 are 10 respectively supported from the upper and lower headers by means of glass-to-metal seals indicated at 25 and 26. The envelope as a whole may be exhausted and sealed off through a tubulation 27 provided in connection with the upper header. 15

Referring more specifically to the header structures, it is desirable that these structures be 20 hermetically sealed to the main body of the envelope. To this end, it is expedient to join the flanges 19 and 20 to the inner surface of the 25 cylinder 11 by line welding. This can be done effectively however, only if the thickness of the header material is approximately the same as that of the cylinder 11, that is to say, of the thickness on the order of 100 mils or less. In 30 connection with the traverse portion of the header, however, the use of a metal of this thinness raises the danger of distortion of the header due to pressure differences existing between the exterior and the interior of the envelope. Assuming 35 that the latter is substantially completely evacuated, a relatively great total pressure may be exerted on the header surface if the header diameter is on the order of several inches or more. 35

Considerations of economy make it desirable 40 that the header and its flange be of substantially uniform thickness so that the header can be spun or formed from a single piece of metal. It is, therefore, not expedient to make the central portion of the header greater in thickness than the flange. In order to overcome this difficulty, my invention provides in connection with the transverse header portion, a reinforcing plate which is integrally secured to the header surface so as 45 to prevent any distortion thereof.

In connection with the upper header 17 there is shown a plate 30 which is applied to the outer surface of the header. This plate may have a 50 thickness materially greater than that of the header, say on the order of $\frac{1}{8}$ inch, and may comprise any suitable structural material such as steel. In order that it may adhere firmly to the header, I provide a brazed connection formed 55 by the interposition of a suitable brazing material such as copper. The structure thus realized assures sufficient rigidity to avoid distortion due to pressure differences and, at the same time, does not destroy the advantages associated with 60

the use of a header element which is of uniform thickness throughout.

In connection with the lower header 18, there are provided reinforcing plates 33 and 34 respectively applied to the inner and outer surfaces of the header. These plates are applied by brazing as described in connection with the plate 30. The presence of the layers of brazing material is indicated at 35 and 36 in Fig. 2, which comprises an enlarged view of a fragmentary section of the header 18 and its associated parts. The brazing layers are actually very thin, say on the order of 5 mils, and may be initially applied in the form of disks of this thickness. The brazed joint is formed by heating the assembly of parts in a brazing furnace.

The plates 33 and 34 are respectively provided with openings 37 and 38 through which there extends a lead-in conductor 39 for the electrode 23. Externally of the envelope this conductor is insulated by means of a series of insulating beads 40. A heavy connection stud 41 is secured to the lower reinforcing plate 35 for supplying current to the cathode 22.

In Fig. 3, a further application of my invention is illustrated in connection with a discharge device in which the main body of the envelope comprises an elongated glass cylinder 42. This cylinder encloses electrodes 43, 44 and 45 and is provided internally with a cooling coil 46 which extends longitudinally of the envelope. The upper end of the envelope is of reduced cross section and is closed by means of a glass-to-metal seal 47 from which the anode 43 is supported. The lower end of the envelope, however, is closed by a transverse header 49 which is, in many respects, similar to the headers described in connection with Figs. 1 and 2. In the present connection, however, it is desirable that the header 49 be constituted of a material which is capable of being sealed directly to glass such, for example, as the alloy of 18% cobalt, 28% nickel and 54% iron described in Burger and Hull Patent No. 2,071,196.

Since the alloy above referred to is expensive, it is desirable to use only a thin section of it. This may be done without encountering danger of distortion of the header if its central region is reinforced in accordance with the principles of my invention. As in the cases previously described, this is done by the application of a steel backing plate 55, which is brazed or other wise secured to the header.

An opening provided in the backing plate accommodates the supporting structure for the electrode 44. As illustrated, this structure comprises a flanged sleeve 56 which is joined to the header as by welding thereto and an interfitting thimble 57 which is hermetically joined at its outer edge to the sleeve 56. A body of glass 59 supports the electrode 44 from the thimble 57 and provides a seal for a lead-in connection to the electrode. The current supply connection for the cathode comprises a heavy stud 60 which is secured to the reinforcing plate 58.

The header 49 is provided with a peripheral flange 50 having a reversely bent portion 51 which is sealed directly to the end of the envelope cylinder so as to provide a glass-to-metal joint at 53. This reversely bent portion, taken in connection with the main flange portion 50, serves to

protect the glass-to-metal seal from excessive stress due to expansion of the header parts. It will be seen that the "goose-neck" provided by the bent flange affords considerable flexibility in which expansive stresses can be taken up. This flexibility is increased by the thinness of the header material, which may be on the order of 100 mils or less.

While I have described my invention in connection with particular embodiments thereof, it will be understood that numerous modifications may be made by those skilled in the art without departing from the invention. I therefore aim in the appended claims to cover all such equivalent variations as fall within the true spirit and scope of the foregoing disclosure.

What I claim as new and desire to secure by Letters Patent of the United States is:

1. A discharge device including electrode structure, an evacuated envelope enclosing the electrode structure, a metallic header closing one end of the envelope and peripherally joined thereto, the said header having a thickness on the order of 100 mils or less so as to facilitate the creation of a hermetical joint with the envelope and a metallic reenforcing plate having a thickness greater than the header thickness and integrally joined to a surface of the header so as to prevent deformation thereof by pressure differences existing between the interior and the exterior of the envelope.

2. A discharge device including electrode structure, a cylindrical metal envelope, a metal header closing one end of the envelope and having a flange which is continuously peripherally welded to the header, the said header having a thickness on the order of 100 mils or less so as to facilitate the welding operation, a reenforcing plate having a thickness greater than the header thickness, and a layer of brazing material rigidly joining the reenforcing plate to a surface of the header so as to prevent deformation thereof by pressure differences existing between the interior and the exterior of the envelope.

3. A discharge device including electrode structure, an enclosing envelope comprising an elongated glass cylinder, a dished metal member forming a header and a peripheral flange continuous with the header, a sealed joint formed directly between the edge of the flange and the glass envelope, the metal member having a thickness on the order of 100 mils or less whereby the said flange is sufficiently flexible to prevent excessive stressing of said sealed joint by expansion of the header, and a reenforcing plate integrally joined to a surface of the header to prevent deformation thereof by pressure differences existing between the interior and the exterior of the envelope.

4. A discharge device including electrode structure, an enclosing envelope comprising an elongated glass cylinder, a dished member of thin metal forming a header and a flange continuous with the header, the said flange being provided with a reversely bent peripheral portion which is sealed at its edge directly to the glass envelope, and a reenforcing plate joined to the central portion of the header so as to increase its rigidity without decreasing the flexibility of the flange.

OTIS W. PIKE.
